(57) **CLAIM**

The ornamental design for a floating island, as shown and described.

DESCRIPTION

FIG. 1 is a front perspective view of a floating island showing my new design.

FIG. 2 is a front view thereof.

FIG. 3 is a rear view thereof.

FIG. 4 is a left view thereof.

FIG. 5 is a right view thereof.

FIG. 6 is a top view thereof; and,

FIG. 7 is a bottom view thereof.

The broken lines shown in the figures represent portions of the floating island that form no part of the claimed design.
